UNITED STATES PATENT OFFICE.

SAMUEL N. CURTISS AND THEODORE CURTISS, OF READING, MICHIGAN.

CUSPIDOR FOOT-REST.

SPECIFICATION forming part of Letters Patent No. 240,011, dated April 12, 1881.

Application filed January 31, 1881. (No model.)

To all whom it may concern:

Be it known that we, SAMUEL N. CURTISS and THEODORE CURTISS, of Reading, Hillsdale county, Michigan, have invented an Improvement in Cuspidor Foot-Rests, of which the following is a specification.

The nature of this invention relates to certain new and useful improvements of combined foot-rests and cuspidors; and the invention consists in the peculiar construction and arrangement of parts by means of which the top of the foot-rest is raised, disclosing a cuspidor, all as more fully hereinafter set forth.

15 Figure 1 is a vertical cross-section with the top opened. Fig. 2 is a vertical longitudinal section with the cover closed.

In the accompanying drawings, which form a part of this specification, A represents a 20 foot rest or stool, the top B of which is upholstered, as shown, and hinged at its rear side to the body.

25 a is a hook projecting from the inner face of the cover or top, and is designed to engage with the spring-latch C, which is pivotally secured to the inner face of one of the legs, its lower end being provided with a proper knob, b, by means of which the latch may be withdrawn from its engagement with the hook a.

30 In one end of the body of the stool we secure a threaded bolt, c, upon which is threaded the spring-block d, being held in place by the jam-nut e.

D is a coil-spring placed upon the spring-block, one end of said spring being secured to the block while the opposite end is looped to embrace the guide-rod E, projecting from the inner face of the cover or lid.

35 F represents a cuspidor, which sits within 40 the body of the device, as shown.

The inner face of the cover or top is padded, preferably with oil-cloth. When the cover is closed the padding on the cover fits closely down upon the top of the cuspidor, and this 45 prevents any possibility of spilling the contents of the cuspidor should the stool be accidentally overturned.

When it is desired to use the cuspidor it is

only necessary to press the foot upon the knob b, which will release the spring-latch from the 50 hook, and the spring will cause the lid or top to fly open. Should the spring D become too weak, from long usage, to open the cover, the tension of the spring may be increased by turning the spring-block farther onto the bolt 55 and again secure it to place by screwing up the jam-nut.

By this construction we produce an article of furniture that is both useful and ornamental as a foot-rest, and which incloses a spittoon or cuspidor, hiding it from view except when required for use.

What we claim as our invention is—

1. A foot rest or stool the top of which is hinged to the body, substantially as described, 65 in combination with a spring-latch and hook for holding said cover closed, substantially as set forth.

2. A foot rest or stool the top of which is hinged to the body and provided with a spring-latch and hook for keeping the cover in its closed position, in combination with a spring 70 for opening said cover, substantially as specified.

3. A foot-rest constructed substantially as 75 described, and adapted to receive a spittoon or cuspidor, in combination with the spring D, spring-latch C, and hook a, substantially as set forth.

4. A foot-rest, the top of which is hinged to 80 the body and provided with a spring for opening said top, in combination with the spring-block d, bolt c, and nut e, for the purpose of regulating the force or tension of said spring, substantially as specified.

5. A foot-rest, in combination with a cuspidor inclosed within the body of said rest or stool, the top of which is adapted to form a water-tight cover to such cuspidor, substantially as set forth.

SAMUEL N. CURTISS.
THEODORE CURTISS.
